UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,204,192.

Specification of Letters Patent. Patented Nov. 7, 1916.

Application filed May 2, 1914. Serial No. 835,791.

To all whom it may concern:

Be it known that I, LYMAN R. ROBERTS, a citizen of the United States, residing in Rutherford, in the county of Bergen and State of New Jersey, have invented certain new and useful Improvements in Type-Writing Machines, of which the following is a specification.

This invention relates to improvements in the construction of the type-bars and their stops, used in typewriting machines.

One object of this invention is to reduce the noise caused by the operation of the machine, by providing a suitable noise-deadening stop in place of the usual solid metal stop, to arrest the type-bars, or carriers, just before the types thereon reach the platen.

My improved stop is of suitable material, and may be made of felt, subjected to great pressure, which renders it almost solid, without the loss of any of its noise-deadening qualities.

It is understood that the usual stop employed for type-bars to arrest them in their type printing action is located in such position in the path of said type-bars as to become effective just a shade in advance of the contacting position of a type carried thereby with relation to the platen surface, and that the impression stroke of a type-bar, through its acquired momentum and the inherent spring-like character of type-bars, causes the type-bar to impel the type into its impacting impression contact.

The cushioned stop which is the subject of this invention has substantially the same relation to the type-bars with regard to its position in their path, but it has the further function of absorbing the shock consequent upon the impression stroke and of deadening the noise attendant thereon. The type-bars operating in conjunction with this stop are provided with broad soles, with which to make impact upon a relatively large area of the surface of the stop, to avoid noise and also to prevent cutting the material of said stop through constant usage. The improved stop serves as a damper to prevent excessive vibration of the type-bar, when suddenly arresting the latter in its movement, thereby avoiding the creation of the humming sound to which type-bars are subject when arrested by an inflexible stop.

Other features and advantages will appear hereinafter.

In the drawings accompanying this application: Figure 1 is a side elevation, showing, in section, a portion of a type-writing machine frame, with my improved type-bar stop, and the relation thereto of type-bars and platen. Fig. 2 is a perspective detail view, partly broken away, of the type-bar stop. Fig. 3 is a partial plan view of several type-bars, extended, showing their impacting surfaces. Fig. 4 is a perspective elevation of a type-bar, and Fig. 5 is a front view of my improved type-bar stop with a type-bar arrested thereby.

In the usual type of Underwood typewriting machine, with which my present invention is shown as applied, the depression of one of the type-keys 1 rocks a bell-crank 2, to swing a bar 3 with its type 4, upwardly between a guide 5 against a platen 6. To secure a clear impression, the bar 3 is arrested in its movement just before the type 4 reaches the platen, so that the free end of the type-bar carrying the type will spring forwardly due to the flexibility of the bar.

The type-bars 3 are arrested in their upward movement by a noise-deadening pad 7 which is held by hooks or claws 8 on a retaining plate 9, which is fastened to the type-bar hanger 10, with screws 11. Said pad is substantially of crescent-shape, coinciding with the curvature of the segmental type-bar hanger 10, to arrest any type-bar that may be actuated.

To prevent the pad from being cut by the type-bars, the latter are provided with broad soles 12, to afford contacting surfaces of relatively large areas. The said soles are arranged one on each side of a type-bar, in the example shown herein, and may have the staggered relation indicated for the purpose of economizing space, while presenting equal bearing surface at opposite sides of the type-bar. It is to be observed that these soles extend laterally in opposite directions at right angles to the plane of the type bars and that their front or impact faces are disposed in advance of the front edges of the type bars (i. e., the edges of the bars which face the platen during the movement of said bars toward said platen). In this way the soles act to positively prevent the aforesaid bar edges from striking

against the pad or cushion at the moment of impact, with the result that injury to the pad is completely avoided.

Variations may be resorted to within the scope of the invention, and portions of the improvements may be used without others.

Having thus described my invention, I claim:

1. In a typewriting machine, the combination with a platen, of a type-bar, an operating key therefor, and a noise-deadening stop of slightly compressible material arranged in the path of the type-bar and in position to arrest the stop-engaging portion of the type-bar before the type thereon reaches the platen, and permitting the type to be carried by momentum to the platen after the stop-engaging portion is arrested, the type-bar formed with broad soles projecting at opposite sides of the type-bar and presenting a large stop-engaging surface to prevent the type-bar from wearing or cutting into said stop.

2. In a typewriting machine, the combination of a platen, a series of type-bars formed of resilient material and arranged to swing to the platen, keys for individually operating the type-bars, and a stop consisting of sound-deadening material positioned to arrest the type-bars before the types carried thereon reach the platen, said type-bars having broad soles arranged to impact with relatively large areas of the stop when engaging the latter, said soles arranged on each side of the type-bars in staggered positions, the resistance of the stop being sufficient to bring the impacting portions of the type-bars to a full stop before the types reach the platen, the resiliency of the type-bars permitting the types to be carried by momentum to the platen.

3. In a typewriting machine, the combination with a platen, of a type-bar arranged to be swung against the platen, a compressed felt stop in the path of the type-bar and positioned to arrest the type-bar as it nears the printing position, the type-bar being formed with a broad sole arranged to strike the stop and thereby prevent the type-bar from cutting into the stop, the latter operative to arrest the swinging movement of the type-bar, bringing the stop-engaging portion thereof to a full stop before the type strikes the platen, and a retainer provided with claws to hold the material of said stop in position.

4. In a typewriting machine having a platen, a series of type-bars arranged to swing toward said platen, and a cushioning stop in the path of movement of said type-bars, to be struck by them just before the types thereon make impact with said platen, adjacent type-bars having staggered enlarged surface-contacting portions for engagement with said stop, the area of said

contacting portions being sufficient to limit the compression of the stop due to the impact of the type-bars and bring said contacting portions to a stop before the types make impact with the platen.

5. In a typewriting machine having a platen, the combination of a pivoted type-bar carrying a type to swing to printing position at the platen, said type-bar formed of springy material, and a stop of sound-deadening material in the path of the type-bar and positioned to be engaged by the type-bar as the type nears the printing position, the stop-engaging portion of the type-bar being nearer to the pivot than to the type, said stop being formed of nearly solid material and having a solid backing, whereby said stop-engaging portion of the type-bar is brought to a stop before the type reaches the printing position, the type stroke being completed by momentum; the type-bar having enlarged stop-engaging surfaces projecting beyond the opposite sides of the body of the type-bar.

6. In a typewriting machine having a platen, the combination of a set of pivoted type-bars carrying types arranged to swing to a common printing center, and a sound-deadening stop in the path of the type-bars and positioned to engage portions of the type-bars nearer to their pivots than to the types thereon, as the types approach printing position, each type-bar having enlarged surfaces or soles extending in staggered relation in opposite directions from the body of the type-bar in position to engage said stop, the soles which extend in one direction from the bars being out of alignment with the soles which extend in the opposite direction, whereby interference between the soles on adjacent bars is prevented, said stop being in position to be engaged by the soles of the type-bars and arrest the same just before the types reach the printing point, the type-bars being resilient to enable the throw of the types to be completed by momentum after the arrest of the stop-engaging portions of the type-bars.

7. In a typewriting machine, the combination, with a platen, of a swinging type-bar; and a cushion disposed in the path of the type-bar for arresting its swinging movement just before the type-carrying end of the bar reaches the platen, so as to cause said end to spring by momentum to said platen; said type-bar having an impact projection thereon which is positioned to directly strike the cushion, and which extends in advance of the forward edge of the bar, to prevent said edge from contacting with said cushion.

8. In a typewriting machine, the combination, with a platen, of a swinging type-bar; and a cushion disposed in the path of the type-bar for arresting its swinging

movement just before the type-carrying end of the bar reaches the platen, so as to cause said end to spring by momentum to said platen; said type-bar having an impact projection thereon which is positioned to directly strike the cushion, and which extends laterally to one side of the bar, with its impact face located in advance of the forward edge thereof, to prevent said edge from 10 contacting with said cushion.

9. In a typewriting machine, the combination, with a platen; of a swinging type-bar; and a cushion disposed in the path of the type-bar for arresting its swinging movement just before the type-carrying end of the bar reaches the platen, so as to cause said end to spring by momentum to said platen; said type-bar having a pair of impact projections thereon which are positioned to directly strike the cushion, and which extend in opposite directions at right angles to the plane of the bar, with their impact faces located in advance of the forward edge thereof, to prevent said edge 20 from contacting with said cushion.

10. In a typewriting machine, the combination, with a platen; of a swinging type-

bar; and a cushion disposed in the path of the type-bar for arresting its swinging movement just before the type-carrying end of the bar reaches the platen, so as to cause said end to spring by momentum to said platen; said type-bar having a pair of projections disposed on opposite sides thereof and provided with flat impact surfaces arranged in position to directly strike the cushion.

11. In a typewriting machine, the combination, with a platen; of a swinging type-bar; a cushion of yielding material disposed in the path of the type-bar; and a retainer provided with claws engaging said cushion to hold the latter in place; said type-bar having an impact projection which is positioned thereon to directly strike the cushion just before the type-carrying end of the bar reaches the platen, so as to arrest the swinging movement of said bar and thereby cause its said type-carrying end to spring to said platen by momentum.
